CONTAINER

Harold Gar Vaughn, Warren, Ohio, assignor to
 The Ohio Corrugating Company, Warren, Ohio,
 a corporation of Ohio

Application November 15, 1935, Serial No. 49,901

16 Claims. (CL 220—61)

This invention relates to a container which has a large opening at one end and a cover therefor adapted to be sealed circumferentially to form a liquid tight container for foods, fluids, semi-fluids, greases and other materials. In the illustrated application of my invention, the body of the container is entirely open at one end and the head for such end is removable and constitutes a cover. By preference, all portions of the container are 10 formed of sheet steel.

In such containers employing split rings for securing and sealing a cover or the container head in position, of which I have knowledge, it has been the practice in some cases for the container manufacturer when shipping empty containers to his customer or user, to position the cover on the container and to clamp the split ring in its operative position thereon with the sealing gasket in its final compressed condition, as no provision was made for effecting or permitting the assembly of these parts without compressing the gasket. Such assembly and shipment resulted in materially affecting the elasticity or expansion and compressibility of the gasket and 25 caused it to become set, so that when the user opened the container and filled it, the gasket had to be discarded and a new one substituted to insure a liquid-tight sealing condition of the filled container for shipment. In other cases, the container manufacturer shipped the gaskets separately and the cover, container and ring in assembled relation, the result being that the cover was loose and permitted dust and dirt to get into the container.

One object of the invention is to provide for a container an improved split ring having on its end portions detachable locking elements so constructed that the ring may be positioned in assembled relation to the container and its cover 40 without compressing the cover gasket to permit shipment of the container in empty condition and after the container is filled to permit the positioning of the ring in final position with the container cover sealed in a liquid-tight manner.

Another object of the invention is to provide for a container of this type an improved closing, sealing and locking means comprising a split ring and a locking means for the ring the construction of which is simplified and arranged to facilitate the positioning of the ring, the assembly of the ring, gasket and container for shipment when empty without destroying the sealing effect of the gasket and the final sealing of the cover and locking of the ring ends together.

Another object of the invention is to provide for a container an improved split ring having on its end portions and below the ring and operable relative to the external side wall of the container, detachable locking elements and a combined lock and sealing means for one of the locking elements.

A further object of the invention is to provide an improved split ring having on its ends locking elements and a lock for such elements arranged to rigidly hold them in operated position and to permit sealing thereof in a ready manner.

A further object of the invention is to provide for a container an improved split ring having on its ends locking means permitting the ring to be assembled on the container in gasket sealing and non-sealing positions and a lock for holding the locking means in either position.

A still further object of the invention is to provide means for reinforcing the ring ends whereby the ring may be made from relatively light gage material.

Other objects of the invention will be apparent to those skilled in the art to which my invention relates from the following description taken in connection with the accompanying drawings, wherein

Fig. 1 is a plan view of a container and its sealing ring, the latter being shown in expanded position and the locking means detached.

Fig. 2 is a fragmentary plan view of the parts shown in Fig. 1, enlarged, but showing the locking means attached and the ring partially closed.

Fig. 3 is a fragmentary view similar to Fig. 2, but showing the ring in final sealing or locked position.

Fig. 4 is a side elevation of the parts shown in Fig. 3.

Fig. 5 is a section on the line 5—5 of Fig. 3.

Figs. 6, 7, and 8 are sections on the lines 6—6, 40 1—7 and 8—8, respectively, of Fig. 4.

Fig. 9 is a section on the line of 9—9 of Fig. 8.

Fig. 10 is a perspective detail view.

Fig. 11 is a fragmentary plan view similar to Fig. 3, but showing the position of the ring when the container is shipped empty.

Fig. 12 is a section on the line 12—12 of Fig. 11.

The container illustrated is of the steel drum or barrel type, having a side wall 1, a cover 2 and a bottom wall or head 2a. The side wall 1 is provided with the usual rolling hoops 1a. The upper end of the side wall is rolled over outwardly to form a continuous circumferential bead 3 and the cover 2 has a circumferential wall or flange 4 arranged to engage a packing or gas- 55

ket 5 seated on the bead 3 and effect a closing and sealing of the container. The cover is preferably cup-shaped so as to fit or telescope within the open end of the side wall 1, the flange 4 projecting outwardly to lie over the packing 5.

6 indicates a split ring substantially U-shape in cross section and when positioned, the ring surrounds the bead 3 and its upper and lower circumferential terminating walls 6a, 6b, engage 10 the flange 4 and lower side of the bead 3 to effect sealing of the cover in position when the ring is contracted. The ring 6 is preferably formed of resilient metal, whereby it may be readily expanded circumferentially and its ends 15 separated substantially laterally sufficiently to permit the ring to be positioned around the bead and flange and then contracted circumferentially into engagement therewith, as shown in Figs. 3, 4, 5, 6, 7 and 8, in which position the 20 cover flange 4 is secured in sealed relation to the bead 3. The operation of contracting the ring into the position indicated is accomplished as hereinafter set forth.

7 indicates as an entirety locking means carried entirely on and below the lower wall 6b of the ring adjacent the ends thereof and within the outer wall of the hoops 1a, whereby the barrel or container may be rolled without danger of damaging the locking means and when the ring 30 is expanded it may be dropped on and supported by the uppermost hoop; for example while the container is being filled and the cover and gasket are being assembled. The operable elements of the locking means are carried by one ring end 35 and are adapted to be detachably connected to the other end of the ring (see Fig. 1) and operated to lock them together. When the locking means are operated into their locked position, the compressibility of the packing 5 allows 40 the ring to contract slightly circumferentially, as shown in Figs. 3, 4, 6 and 7; as a result of this contraction the upper and lower walls 6a, 6b, serve to draw the cover flange 4 and bead 3 together, with the gasket compressed between 45 them, in which position the cover is tightly held and sealed by the locking means.

For this purpose I secure exteriorly on one ring end, as by welding, a wall 8 having a depending support 8a which is provided at its lower 50 end with an outwardly extending lug 8x. The lug 8x is preferably extended toward the other ring end and such extended end has pivoted to it on a vertical axis 8' the inner end of a lever 9, adapted to serve as a handle. The lug 8x is folded back on itself to form a relatively thick 55 wall through which the pivot pin 8' extends. The lever 9 is substantially U-shape in cross section to effect a reinforcement thereof and permit its side walls at their inner ends to fit over 60 the lug 8x and pivotally engage the opposite ends of the pin 8'. 10 indicates a link, preferably two links, pivotally connected by a vertically disposed pin 9' at one end to the opposite sides of the lever 9 at a point remote from its pivot 8'. 65 The opposite or free ends of the links 10 are provided with a pin 11 adapted to provide for the detachable connection of the links to the other end of the ring. The other ring end is provided with a wall 12, welded exteriorly thereto and 70 having a depending support 12a provided at its lower end with an outwardly extending lug 13 which is doubled back on itself to form a relatively thick wall. The outer longitudinal edge of the lug 13 is formed with a plurality of notches 75 14, 14a into any one of which the pin 11 may be

inserted, as later set forth, following which the lever 9 may be operated from the Fig. 2 position inwardly, horizontally toward and substantially into engagement with the side wall 1, thereby securing the cover, gasket, container and ring in assembled relation. When the lever or handle 9 is operated into this position it may be locked and sealed at its outer end against tampering by means, indicated as an entirety at 15. I prefer to provide two notches 14, 14a, spaced 10 longitudinally of the ring. When the pin 11 is inserted in the notch 14a remote from the adjacent ring end and the lever 9 is operated as above set forth (see Figs. 3, 4, 5, 6, 7 and 8), the ring is contracted into final position, the gasket 15 5 being compressed to seal the cover. When the pin 11 is inserted in the notch 14 near the adjacent end of the ring and the lever is operated as above set forth (see Figs. 11 and 12), the ring is contracted to a limited extent to avoid compressing the gasket and thus making it ineffective as a seal; but such contraction is sufficient 20 to secure the cover, gasket, container and ring in assembled relation. Accordingly, the container manufacturer may make and assemble 25 these parts and ship them in assembled relation (the container empty) to the container user without distorting the gasket or affecting its sealing characteristic and the user may readily remove the gasket and cover 2, fill the container, 30 and then replace the gasket and cover, and operate the locking means 7 in the manner later set forth and thus compress the gasket to effect sealing of the cover in a liquid-tight condition. 35

It will be noted that the notch 14 nearest the adjacent ring end extends substantially radially of the container and at its inner end it is enlarged to form shoulders 14' and that the notch 14a remote from the adjacent ring end is, by preference, inclined outwardly and away from 40 such end, but is enlarged at its inner end to form a shoulder 14' at the inner end of its rear wall. The shoulders 14' provide a positive engagement for the pin 11 when applying or removing the ring, as later set forth. 45

The operation of contracting the ring, after it is positioned as shown in Fig. 2, may be accomplished in various ways, for example, by imparting thereto several taps or blows at varying points around its circumference and thereafter operating the handle to the position shown in Figs. 3, 4 and 6. Such contraction serves to force the cover flange 4 throughout its circumference toward the bead 3 substantially axially of the container, thereby uniformly compressing 55 the packing 5 and effecting a liquid-tight seal for the container. By preference, the ring is applied as follows: the pin 11 is inserted in the notch 14 and the lever 9 operated to its closed position as shown in Fig. 11, thereby partially 60 sealing the cover in position without compressing the gasket to any substantial extent (see Fig. 12). This operation is followed when the container is to be shipped empty. To remove the ring, the lever 9 is swung outwardly, which operation expands the ring so that it may be removed or dropped onto the hoop, as already set forth. When the container is filled and the cover is to be sealed to protect its contents during shipment, the above contraction operation is 65 first carried out to effect partial contraction of the ring; then the pin 11 is removed from the notch 14, the lever 9 is swung outwardly and the pin 11 is inserted in the notch 14a, following 70 which the lever 9 is again swung to its closed 75 position.

position, as shown in Figs. 3, 4 and 6, thereby effecting a final contraction of the ring and sealing of the cover.

To remove the ring, the lever is first swung outwardly, the effect of which is to partially expand the ring; thereafter the pin 11 is removed from the notch 14a and inserted in the notch 14, following which the lever 9 is again operated outwardly, the effect of which is to further expand the ring 6, which may then be lifted bodily from the container or allowed to drop down on the uppermost rolling hoop. With the ring expanded into the position just described, if removed from the container, it may be positioned over the cover in a ready manner and contracted as above set forth.

From the foregoing description it will be seen that the locking means between the ring ends provide for two conditions, one where the parts 20 may be assembled, with the container empty, and shipped to the user while maintaining the gasket in position and substantially uncom- 25 pressed and the other where the user, after filling the container, may quickly and easily, by operation of the locking means, contract the ring to seal the cover in final position and the receiver may with equal facility remove the ring. As the ring in its sealing position compresses the gasket substantially to the limit of its com- 30 pressibility and often tends to stick to the ring wall, the adjustable attachment and detachment of the locking and operating elements, as above set forth, provides for a positive as well as a ready means for expanding or contracting the ring, 35 both initially and finally, and handling thereof.

When the lever 9 is operated to the position shown in Figs. 3, 4, 6 and 11, an imaginary line extending through the axes of the pivot 9' and pin 11 lies inwardly of the axis of the pin 8'; 40 accordingly, the lever 9 when in closed position against the side 1 of the container is locked against outward movement.

In the arrangement shown, the inner end of the lever straddles the lug 8x and the links 10 straddle the lever 9 and lug 13 and as the lugs 8x and 13 are disposed in the same plane the locking action of the locking means is transmitted in the plane of the lugs and substantially in a direction parallel to the plane of the ring, 45 so that in the contracting and expanding operations of the latter, due to operation of the lever 9, no twisting forces are imparted to the ring ends and the upper and lower walls of the ring move substantially at right angles to the axis of the container.

The lever 9 is curved from end to end so as to lie concentric to the side wall 1 when in operated position.

The combined lock and sealing means 15 are arranged to connect the lever or handle 9 to an adjacent portion of the ring and the elements of these means are arranged so as to provide frictional engagement one with another under tension so as to prevent their accidental detachment and vibration due to bodily handling or rolling of the container. Of these means, 16 indicates an angle on the outer end of the lever 9 to provide a vertical wall 17 and a lateral wall 18, which is bent downwardly for clearance purposes. The angle 16 is preferably provided by slitting the lower side of the lever at 16' and bending such side down to a position at right angles to the upper side of the lever. 19 indicates a slot formed in the wall 18 and extending inwardly from its free end longitudinally ad-

jacent to the inner face of the wall 17 and adapted to receive a latch 20. The latch 20 is pivotally connected at its upper end to a lug 21 depending below the lower ring wall 6b, the lug 21 being integrally connected to a wall 21a welded exteriorly to the ring 6 as shown in Figs. 4 and 8. The pivot 20' for the latch 20 extends substantially radially of the axis of the ring and is arranged inwardly of the free end of the lever 9 (when the latter is in operated or closed position, see Figs. 4, 5 and 11), the latter being supported by depending members 8a and 12a in a plane below such pivot 20'. In this arrangement the latch 20 may be swung outwardly to a position out of the path of movement of the lever 9, as shown in Fig. 9, and then swung downwardly to its vertical position and into the recess or slot 19 (see dotted lines in Fig. 9 and full lines in Figs. 4 and 8), thereby locking the lever or handle 9. The latch 20 is preferably 20 slightly out of alignment with one wall of the slot 19, so that it has to be forced thereinto, the effect of which is to provide a resilient, sliding contact between their walls to prevent these parts from vibrating. To facilitate entering the latch 20 into the slot 19, it is provided with a beveled wall 19'. The free end of the latch 20 is provided with an inturned end 22 which serves as an extension to facilitate swinging the latch into and out of locking position. The wall 17 30 and latch 20 are formed with openings 23, 23', respectively, adapted to register, when the lever 9 is in closed position and the latch 20 is in locking position, and to permit a wire 24 to be threaded through them and their ends connect- 35 ed by a seal slug 25.

26 indicates an auxiliary lock between the lever 9 and latch 20 serving to hold the latter in a predetermined position, that is, that position in which the openings 23, 23', are in registry, the purpose being to prevent accidental disengagement of the latch from the lever or relative movement between them, whereby the sealing wire 24 might become cut. The auxiliary lock 26 preferably consists of an indentation 26' formed in one part, to wit, the latch 20 and an embossed projection on the inner face of the wall 11, which projection is adapted to ride the wall of the latch 20 and drop into the indentation 26' as shown in Fig. 8.

The walls 8 and 12 are arranged adjacent the ends of the ring and serve to reinforce the ring so that the latter may be made of light gage material.

To those skilled in the art to which my invention relates, many changes in construction and widely differing embodiments and applications of the invention will suggest themselves without departing from the spirit and scope of the invention. My disclosures and the description herein are purely illustrative and not intended to be in any sense limiting.

What I claim is:

1. In a container construction having a circumferential bead at its upper end, the combination with a gasket arranged to engage the bead and a cover having a peripheral flange arranged to engage the gasket, of a split channel ring arranged to surround the bead and cover flange and pivotally connected locking elements 65 one of which is pivotally connected to the lower wall of said ring adjacent one end thereof and adapted to be detachably connected to one portion of said lower wall adjacent the other ring end and operated to closed position to hold the 70 75

- container, gasket and cover in assembled relation and adapted to be detachably connected with a remote portion of said lower wall of the other ring end and operated to closed position
- 5 to clamp the cover flange and bead together with the gasket compressed between them, said locking elements when in closed position being disposed entirely within the outer circumferential wall of said ring.
- 10 2. In a container construction having a circumferential bead at its upper end, the combination with a gasket arranged to engage the bead and a cover having a peripheral flange arranged to engage the gasket, of a split channel ring arranged to surround the bead and cover flange, locking elements carried by the lower wall of said ring adjacent one end thereof, one of said elements being provided with an engaging member, and a wall carried by the lower ring wall adjacent the other end thereof and formed with a notch adjacent said ring end adapted to be detachably engaged by said engaging member whereby operation of said elements to closed position will hold the container, gasket and cover in assembled relation, said wall being formed with a second notch remote from said ring end and adapted to be detachably engaged by said engaging member whereby operation of said elements to closed position will clamp the cover flange and bead together with the gasket compressed between them, said locking elements when in closed position being disposed within the outer circumferential wall of said ring.
- 15 3. In a container construction having a circumferential bead at its upper end, the combination with a gasket arranged to engage the bead and a cover having a peripheral flange arranged to engage the gasket, of a split channel ring arranged to surround the bead and cover flange, locking elements carried by the lower wall of said ring adjacent one end thereof, one of said elements being provided with an engaging member and a wall carried by the lower ring wall adjacent the other end thereof and formed with a notch adjacent said ring end adapted to be detachably engaged by said engaging member whereby operation of said elements to closed position will hold the container, gasket and cover in assembled relation, said wall being formed with a second notch remote from said ring end and adapted to be detachably engaged by said engaging member whereby operation of said elements to closed position will clamp the cover flange and bead together with the gasket compressed between them, the side wall of one of said notches being enlarged at its inner end to form a shoulder for engagement by said member.
- 20 4. In a container construction having a circumferential bead at its upper end, the combination with a gasket arranged to engage the bead and a cover having a peripheral flange arranged to engage the gasket, of a split channel ring arranged to surround the bead and cover flange and engage therewith, locking elements, including a lever, carried by the lower wall of said ring adjacent one end thereof and adapted to be detachably connected to said lower wall adjacent the other ring end to contract the ring into engagement with said bead and said flange, and a latch pivoted on the lower wall of said ring on an axis disposed at right angles to said lever when in closed position and adapted to be swung into said slot when said lever is in operated position, whereby said latch is disposed in the path of movement thereof to lock it.
- 25 5. In a container construction having a circumferential bead at its upper end, the combination with a gasket arranged to engage the bead and a cover having a peripheral flange arranged to engage the gasket, of a split channel ring arranged to surround the bead and cover flange and engage therewith, locking elements, including a lever, carried by the lower wall of said ring adjacent one end thereof and adapted to be detachably connected to said lower wall adjacent the other ring end to contract the ring into engagement with said bead and flange, the outer end of said lever being formed with a longitudinally extending slot and a latch pivoted on the lower wall of said ring on an axis disposed at right angles to said lever when in closed position and adapted to be swung into said slot when said lever is in operated position, whereby said latch is disposed in the path of movement thereof to lock it.
- 30 6. In a container construction having a circumferential bead at its upper end, the combination with a gasket arranged to engage the bead and a cover having a peripheral flange arranged to engage the gasket, of a split channel ring arranged to surround the bead and cover flange and engage therewith, locking elements, including a lever, carried by the lower wall of said ring adjacent one end thereof and adapted to be detachably connected to said lower wall adjacent the other ring end to contract the ring into engagement with said bead and flange, the outer end of said lever being formed with a longitudinally extending slot and a latch pivoted on the lower wall of said ring on an axis disposed at right angles to said lever when in closed position and adapted to be swung into said slot when said lever is in operated position, whereby said latch is disposed in the path of movement thereof to lock it, and auxiliary locking means between the walls of said lever and latch.
- 35 7. In a container construction having a circumferential bead at its upper end, the combination with a gasket arranged to engage the bead and a cover having a peripheral flange arranged to engage the gasket, of a split channel ring arranged to surround the bead and cover flange and engage therewith, locking elements, including a lever, pivoted on a vertical axis on the lower wall of said ring adjacent one end thereof and adapted to be detachably connected to said lower wall adjacent the other ring end, whereby said lever is operable toward the side wall of the container to contract the ring into engagement with said bead and said flange, and a latch pivoted on the lower wall of said ring on an axis substantially radially thereof inwardly of the outer end of said lever when the latter is in operated position and arranged to be positioned in the path of movement of said lever to open position to lock it, said latch being movable to a position beyond the free end of the lever to permit operation of the latter to closed position.
- 40 8. In a container construction having a circumferential bead at its upper end, the combination with a gasket arranged to engage the bead and a cover having a peripheral flange arranged to engage the gasket, of a split channel ring arranged to surround the bead and cover flange and engage therewith, locking elements, including a lever, pivoted on a vertical axis on the lower wall of said ring adjacent one end thereof and adapted to be detachably connected to said lower wall adjacent the other ring end, whereby said lever is operable toward the side wall of the container to contract the ring into engagement with said

bead and said flange, the outer end of said lever being formed with a slot extending longitudinally inwardly, and a latch pivoted on the lower wall of said ring on an axis extending substantially 5 radially of the ring inwardly of the outer end of the lever when the latter is in operated position and arranged to project into said slot to lock the lever in operated position, said latch being swingable to a position beyond the free end of the lever, 10 to permit operation of the latter to closed position.

9. In a container construction having a circumferential bead at its upper end, the combination with a gasket arranged to engage the bead 15 and a cover having a peripheral flange arranged to engage the gasket, of a split channel ring arranged to surround the bead and cover flange and engage therewith, locking elements, including a lever, pivoted on a vertical axis on the lower wall 20 of said ring adjacent one end thereof and adapted to be detachably connected to the other ring end, whereby said lever is operable toward the side wall of the container to contract the ring into engagement with said bead and said flange, the 25 outer end of said lever being formed with a slot extending longitudinally inwardly, and a latch pivoted on the lower wall of said ring on an axis extending substantially radially of the ring inward of the outer end of the lever when the 30 latter is in operated position and arranged to project into said slot to lock the lever in operated position, said latch being swingable to a position beyond the free end of the lever to permit operation of the latter to closed position, and arranged 35 to frictionally engage one wall of said slot when projected thereinto.

10. The combination with a container the side wall of which is provided at its upper end with a circumferential bead and a cover having a circumferential marginal edge arranged to engage 40 said bead, of a split ring substantially U-shape in cross section to provide upper and lower terminating walls arranged to be expanded over said bead and edge and contracted to effect engagement of said terminating walls therewith, whereby said cover is sealed against said bead, and means for contracting said ring, said means comprising a lever and a link pivotally connected to each other and to the lower walls adjacent the 45 ends of said ring, one of said pivotal connections being detachable, said contracting means when in operated position being entirely within the side wall of said ring.

11. The combination with a container the side 55 wall of which is provided at its upper end with a circumferential bead and a cover having a circumferential marginal edge arranged to engage said bead, of a split ring substantially U-shape in cross section to provide upper and lower terminating walls arranged to be expanded over said bead and edge and contracted to effect engagement of said terminating walls therewith, whereby said cover is sealed against said bead, and pivotal locking means for contracting said ring 60 carried on and below said lower wall adjacent one end of said ring and arranged to detachably engage an element fixed to and arranged below said lower wall adjacent the other end of said ring, said means when in operated position being disposed entirely within the side wall of said ring.

12. The combination with a container the side 70 wall of which is provided at its upper end with a circumferential bead and a cover having a circumferential marginal edge arranged to engage

said bead, of a split ring substantially U-shape in cross section to provide upper and lower terminating walls arranged to be expanded over said bead and edge and contracted to effect engagement of said terminating walls therewith, whereby said cover is sealed against said bead, and locking means for contracting said ring arranged when in operated position entirely within the side wall thereof, said means comprising members depending from the lower wall of said ring 10 adjacent its ends and pivotally connected elements, one of said elements being pivotally mounted on one of said members and the other element being provided with a device adapted to detachably engage the other member. 15

13. The combination with a container the side wall of which is provided at its upper end with a circumferential bead and a cover having a circumferential marginal edge arranged to engage 20 said bead, of a split ring substantially U-shape in cross section to provide upper and lower terminating walls arranged to be expanded over said bead and edge and contracted to effect engagement of said terminating walls therewith, whereby said cover is sealed against said bead, and locking means for contracting said ring, said 25 means comprising two pivotally connected elements, one element having a permanent pivotal connection with the lower wall of said ring at one end thereof and the other element being 30 provided with a device adapted for detachable pivotal connection with the lower wall at the other end of said ring, said pivotally connected elements when in operated position being disposed entirely within the side wall of said ring. 35

14. The combination with a container the side wall of which is provided at its upper end with a circumferential bead and a cover having a circumferential marginal edge arranged to engage 40 said bead, of a split ring substantially U-shape in cross section to provide upper and lower terminating walls arranged to be expanded over said bead and edge and contracted to effect engagement of said terminating walls therewith, whereby said cover is sealed against said bead, locking 45 means for contracting said ring carried on and below said lower wall adjacent one end of said ring, the outer end of one element of said locking means being provided with a pivot pin and a wall supported on and arranged below the lower 50 wall of said ring adjacent the other end thereof and formed with a notch to detachably receive said pin, said locking means when in closed position being disposed entirely within the side wall of said ring.

15. The combination with a container the side wall of which is provided at its upper end with a circumferential bead and a cover having a circumferential marginal edge arranged to engage 55 said bead, of a split ring substantially U-shape in cross section to provide upper and lower terminating walls arranged to be expanded over said bead and edge and contracted to effect engagement of said terminating walls therewith, whereby said cover is sealed against said bead, locking 60 means for contracting said ring carried on and below said lower wall adjacent one end of said ring, and a wall supported on and below the lower wall of said ring adjacent the other end of said ring and formed with a plurality of notches each to provide a pivotal, detachable connection by one element of said locking means with said last mentioned wall, said locking means when in closed position being disposed entirely 65 within the side wall of said ring. 70

16. The combination with a container the side wall of which is provided at its upper end with a circumferential bead and a cover having a circumferential marginal edge arranged to engage said bead, of a split ring substantially U-shape in cross section to provide upper and lower terminating walls arranged to be expanded over said bead and edge and contracted to effect engagement of said terminating walls therewith, whereby said cover is sealed against said bead, and locking means for contracting said ring, said

elements comprising lugs carried on and below said lower terminating wall of said ring adjacent the respective ends thereof, a lever and a link pivotally connected to each other, one of said elements being provided with a pin and an adjacent element being provided with a plurality of spaced notches each arranged to detachably receive said pin, said locking elements when in operated position being entirely within the side wall of said ring. 5

HAROLD GAR VAUGHN. 10
